UNITED STATES PATENT OFFICE.

GERTRUDE CHEYNE, OF BOSTON, MASSACHUSETTS.

VEIL-FASTENER.

1,161,799.

Specification of Letters Patent. Patented Nov. 23, 1915.

Application filed July 11, 1913. Serial No. 778,541.

To all whom it may concern:

Be it known that I, GERTRUDE CHEYNE, of Boston, in the county of Suffolk and State of Massachusetts, have invented certain new and useful Improvements in Veil-Fasteners, of which the following is a specification.

This invention relates to an improvement in veil fasteners, and the object of the invention is to provide a simple and efficient device by which the lower edge of a veil may be easily secured about the neck of the wearer, thus enabling the upper portion of the veil to be thrown up over the head or hat of the wearer and fastened, and by which the veil may be adjusted to the wearer's face in a smooth and unwrinkled manner.

With the above object in view, the invention consists in the fastener for veils hereinafter described and defined in the claim.

In the accompanying drawing illustrating one embodiment of the invention, Figure 1 is a view showing a veil with the fastener in place upon the wearer, and Fig. 2 is a fragmentary view of a veil showing the fastener open and secured to the edge of the veil.

As illustrated in the drawing the fastener comprises a band 10, which is preferably made of velvet ribbon or the like, although any other suitable material may be employed. The ends of the band are provided with interengaging fastening means, preferably of the well known ball-and-socket, or glove fastener type. To one end of the band 10 a ball-member 12 is secured, and to the other end of said band a socket-member 14

is secured. The length of the band 10 is such that when clasped about the neck of the wearer it fits comfortably tight.

The band is secured to the middle portion of the edge of the veil 16, preferably by sewing, allowing a slight fullness of the veiling as it is sewed to the band. In use the band is adjusted around the neck, then the veil is thrown up over the hat and tied upon the hat, or the ends secured together in any desired manner. Thus the veil is held firmly at the bottom around the neck and head of the wearer, and can be quickly applied or removed. This fastener is particularly adapted for automobiling as it holds the veil securely against movement by the wind.

Having thus described my invention, what I claim is:—

In combination with a veil of a neck strip therefor comprising an inelastic flexible band secured mid-length one marginal edge of the veil, the veil being slightly full or gathered at its point of connection with the band, said band projecting in part and throughout its length beyond said veil edge, and coöoperating fastening means carried by the respective ends of the band beyond the veil edge.

In testimony whereof I have affixed my signature in the presence of two witnesses.

GERTRUDE CHEYNE.
